APPARATUS FOR HANDLING PACKAGE CARRIERS

Harry S. Drum and William C. Dodson, Abington, and William H. Jaxheimer, Philadelphia, Pa., assignors to Smith, Drum and Company, Philadelphia, Pa., a corporation of Pennsylvania

Application October 19, 1939, Serial No. 300,168

6 Claims. (Cl. 242—130)

The present invention relates to yarn package handling apparatus and more particularly to a package carrier arranged for association with a novel supporting truck.

In the handling of carriers of the type mounting a plurality of yarn packages it has heretofore been the general practice to locate the package carrier in the dye vat with the spindles of the packages in a vertical position and after the dyeing or other treating operation to remove the carrier and place it on a support with the packages in the same relative position as when in the vat, namely, with all spindles still vertically disposed with the present day carriers of large capacity holding hundreds of packages, and with three to four packages on each carrier spindle it is exceedingly difficult to remove and replace the packages. With these large diameter carriers it becomes almost impossible for the operator to reach the packages nearest the center of the carrier without danger of injury to his arm from the exposed sharp threads in the end of each spindle, or without danger of bending the spindles through bodily contact.

Some of the objects of the present invention are to provide an improved method of handling carriers of yarn packages; to provide an apparatus for handling carriers of yarn packages wherein the foregoing disadvantages are overcome; to provide an apparatus wherein provision is made for ready access to any package on a yarn package carrier without interfering with any adjacent packages; to provide an apparatus wherein the centrally located yarn packages on a carrier are brought in position for removal with equal facility to those furthest from the center; to provide means whereby a yarn package carrier can be shifted from its normal plane of operation into another plane convenient for yarn package replacement; to provide a carrier locking means for retaining the carrier in yarn package replacement position; and to provide other improvements as will hereinafter appear.

In the accompanying drawings Fig. 1 represents an end elevation of a carrier handling truck embodying one form of the present invention and showing one form of package carrier mounted thereon in position for the replacement of the yarn packages; Fig. 2 represents a side elevation of the same; Fig. 3 represents a side elevation of the truck with a carrier suspended above ready for placing thereon; Fig. 4 represents a sectional detail of one form of carrier locking means; Fig. 5 represents a detail in section of the mounting for the locking arm; Fig. 6 represents a side ele-

vation in part section of a modified form of the invention showing in full lines the loading position and in dotted lines the position for carrier assembly; and Fig. 7 represents a section on line 7—7 of Fig. 6.

Referring to the drawings one form of the present invention consists of a wheeled truck 10 for association with and support of a carrier of the type having spindles 11 for respectively mounting wound packages of yarn 12. As here shown the carrier has a hollow disc body 13 arranged to support the spindles 11 at opposite sides thereof, each spindle being constructed to communicate with the interior of the body 13 for circulating treating liquid through the yarn packages 12 on the respective spindles. A pipe 14 extends axially from the body 13 and has a tapered end 15 to form a leak proof joint with the coacting seat provided in the vat which is designed to receive the carrier. The opposite side of the body 13 carries an axially disposed post 16 of a length greater than that of the spindles, in order that its free end is accessible to attach a hoisting mechanism. As shown the end of the post 16 is circumferentially grooved to form a head 17 having a truncated end face, and therefore when the gripping jaws 18 on the hoist chain 20 grasp the head 17, the carrier can be suspended for movement from one position to another through the overhead trolley of which the chain 20 forms a part.

In order to support the carrier when released from the jaws 18, two diametrically located trunnions 21 are welded or otherwise made fast to the body 13 and serve as rotatable supporting means to respectively seat on suitable supports.

For the purpose of supporting the carrier and allowing it to be controlled in accordance with the present invention, the truck 10 is formed with two vertical standards 22 so spaced apart as to receive the body 13 of the carrier therebetween and allow the trunnions 21 to respectively seat in suitably shaped bearing sockets 23 in the ends of the respective standards 22. Thus when the carrier is lowered by the hoist into position between the standards 22, the trunnions 21 then support the carrier after the hoist jaws 18 are released. When so initially supported the package spindles 11 are still in the normal, vertical position but by reason of the trunnion action the carrier can now be swung to a position where the spindles 11 are disposed horizontally. Thus in the new position an operator can stand in front of the assembly of packages and remove and re-

place the packages easily and simply without danger.

To prevent the carrier from swinging out of its loading and unloading position, a locking mechanism is provided consisting in the present instance of a cap 24 which is complementarily shaped internally to fit over the head 17 and allow a locking detent 25 to drop into the groove back of the head 17 to thus prevent movement of the carrier post 16. The detent 25 is pivoted at 26 to the cap 24 and has a projecting finger 27 for manual release when necessary. The cap 24 is fast to the upper end of an arm 28 which is mounted for limited swing action on a brace rod 30 of the truck 18. Thus the lower end of the arm 28 joins a tubular sleeve 31 which is rotatable on the rod 30. A stop 32 projects from the arm 28 to ride in a limit slot 33 formed in a housing 34 fixed to the rod 30. This allows the arm 28 to swing outwardly only far enough to 20 remove the cap 24 from the head 17, and is thus kept out of the operator's way.

In operation the carrier may be supported by an overhead hoist in which gripping jaws 18 engage the head 17 and suspend the carrier in a horizontal position with the package spindles vertically disposed. This is the manner in which the carrier is lowered into the vat for dyeing or other treating operations and is removed therefrom. At the end of a treating operation the 30 carrier is brought by the overhead trolley into an overhead aligned relation to the truck and is then lowered so that the trunnions 21 seat in the bearings on the standards 22. When this position has been reached the hoisting mechanism is 35 released and the carrier is then swung to the position where the post 16 is horizontally disposed and in position for registry with the cap 24. This latter is then swung forwardly on its arm 28 and the detent 25 drops into place back 40 of the head 17 to thereby lock the carrier in position while it is being loaded and unloaded.

While in the foregoing a particular type of package carrier is shown, the invention is not limited in this respect as various other types of carriers can be used to carry out the underlying method. Thus the method devised includes as a novel step changing the axial relation of the package spindles from a vertical to a horizontal position or vice versa during the handling of the 50 carrier.

In the form of the invention shown in Figs. 6 and 7 the truck 35 is a three legged type supporting a centrally disposed rigid column 36 which terminates in a bifurcated head 37. Pivotally mounted between the forks of the head 37 is a bracket arm 38 carrying an integral tubular elongated housing 40 provided with a somewhat enlarged receiving end 41. This housing 40 carries as a rigid component part thereof, an axially disposed stem or shank 42 and a portion of which projects from the housing for telescopic engagement with the pipe 14 of the package carrier. This projecting portion is of a size and shape to fit properly within the pipe 14 and extending well through the carrier body so that the latter is entirely stable when assembled in the shank 42. As shown in full lines the weighted housing 40 is in the position to hold the carrier with the spindles 11 horizontal while in dotted lines the housing is shown in position for removing a carrier therefrom or placing a carrier thereon.

In order to prevent axial displacement of the carrier when in loading position, the pipe 14 is 75

provided with a flange 43 arranged to seat back of a locking member 44 which is fixed to the head 37 in correct relation for proper cooperation with the flange 44. Thus as the housing 5 swings from a vertical axis to a horizontal axis with a carrier on the shank 42, the flange 43 will seat back of the member 44 and thus prevent axial movement of the pipe 14 relative to the housing thereby ensuring interconnected relation between the support and carrier while the latter is being loaded or unloaded.

Having thus described our invention, we claim:

1. In an apparatus for handling carriers for yarn packages, the combination of a carrier having a disk body, and a plurality of yarn package spindles projecting from opposite sides thereof, means for attaching an overhead hoist thereto to raise, move and lower said carrier with said spindles vertically disposed, a device for supporting said carrier, and means for rotatably and removably mounting said carrier on said device to swing about a horizontal axis, whereby said spindles can be positioned horizontally for loading and unloading and vertically for yarn dyeing.

2. In an apparatus for handling carriers for yarn packages, the combination of a carrier having a disk body and a plurality of yarn package spindles projecting from opposite sides thereof, means for attaching an overhead hoist thereto to suspend said carrier with said spindles vertically disposed, a device for supporting said carrier, means for rotatably and removably mounting said carrier on said device to swing about a horizontal axis, and means to lock said carrier to said device.

3. In an apparatus for handling carriers for yarn packages, the combination of a carrier having a disk body and a plurality of yarn package spindles projecting from opposite sides thereof, means for attaching an overhead hoist thereto to raise, move and lower said carrier with said spindles vertically disposed, a truck, standards on said truck for receiving said carrier therebetween, and means on said carrier coacting respectively with said standards for rotatably mounting said carrier to swing about a horizontal axis, whereby said carrier can be positioned with said yarn spindles horizontally disposed for loading and unloading packages and vertically for yarn dyeing.

4. In an apparatus for handling carriers for yarn packages, the combination of a carrier having a disk body and a plurality of yarn package spindles projecting from opposite sides thereof, means for attaching an overhead hoist thereto to raise, move and lower said carrier with said spindles vertically disposed, a truck, standards on said truck for receiving said carrier therebetween, means on said carrier coacting respectively with said standards for rotatably mounting said carrier to swing about a horizontal axis, whereby said carrier can be positioned with said yarn packages horizontally disposed for loading and unloading packages and vertically for dyeing, and means to lock said carrier to said truck.

5. In an apparatus for handling carriers for yarn packages, the combination of a carrier having yarn package spindles projecting therefrom, means for attaching an overhead hoist thereto to suspend said carrier with said spindles vertically disposed, a truck, standards on said truck for receiving said carrier therebetween, bearings respectively on said standards, and trunnions on said carrier for respectively seating in said bearings to rotatably mount said carrier to swing

about a horizontal axis, whereby said carrier can be positioned with said yarn spindles horizontally disposed for loading and unloading.

6. In an apparatus for handling carriers for yarn packages, the combination of a carrier having yarn package spindles projecting therefrom, a truck, standards on said truck for receiving said carrier therebetween, means for mounting said

carrier in said truck to swing about a horizontal axis, an arm pivoted to said truck, and means for locking said carrier to said arm with said spindles horizontally disposed for loading and unloading.
